DESIGN.

L. McG. WILLIAMS.

TIMEPIECE HANDS.

APPLICATION FILED JULY 10, 1920.

56,793.

Patented Dec. 14, 1920.

Lois McG. Williams ^{INVENTOR}
By James N. Ramsey
ATTORNEY.

UNITED STATES PATENT OFFICE.

LOIS McG. WILLIAMS, OF FORT THOMAS, KENTUCKY, ASSIGNOR TO ELGIN NATIONAL WATCH COMPANY, OF ELGIN, ILLINOIS, A CORPORATION OF ILLINOIS.

DESIGN FOR TIMEPIECE-HANDS.

56,793.

Specification for Design.

Patented Dec. 14, 1920.

Application filed July 10, 1920. Serial No. 395,387. Term of patent 14 years.

To all whom it may concern:

Be it known that I, Lois McG. Williams, a citizen of the United States, residing at Fort Thomas, in the county of Campbell and State of Kentucky, have invented a new, original, and ornamental Design for Timepiece-Hands, of which the following is a specification, reference being had to the accompanying drawing, forming part thereof.

In the drawing, the figure is a front elevation.

I claim:

The ornamental design for timepiece hands, substantially as shown.

LOIS McG. WILLIAMS.

Witnesses:

JAMES N. RAMSEY,
GLADYS L. HORTON.
